UNITED STATES PATENT OFFICE

155,560

DESIGN FOR A GLASS HOLDER

John W. Toland, Clearwater, Fla.

Application September 9, 1947, Serial No. 141,277

Term of patent 14 years

(Cl. D44—10)

To all whom it may concern:

Be it known that I, John W. Toland, a citizen of the United States, residing at Clearwater, in the county of Pinellas and State of Florida, have invented a new, original, and ornamental Design for Glass Holder, of which the following is a specification, reference being had to the accompanying drawing, forming part thereof.

In the drawing the sole figure is a perspective view of a glass holder embodying my new design.

I claim:

The ornamental design for a glass holder, as shown.

JOHN W. TOLAND.
